UNITED STATES PATENT OFFICE.

GEORGE A. REYNOLDS, OF UTICA, NEW YORK, ASSIGNOR TO THE STANDARD RAILWAY GATE COMPANY.

RAILWAY-GATE.

SPECIFICATION forming part of Letters Patent No. 550,726, dated December 3, 1895.

Application filed February 29, 1892. Serial No. 423,126. (No model.)

To all whom it may concern:

Be it known that I, GEORGE A. REYNOLDS, of Utica, in the county of Oneida and State of New York, have invented certain new and useful Improvements in Railway-Gates; and I do hereby declare that the following is a full, clear, and exact description of the invention, which will enable others skilled in the art to which it appertains to make and use the same, reference being had to the accompanying drawings, and to the numerals of reference marked thereon, which form part of this specification.

My present invention relates to improvements in the mechanism for operating and controlling automatic railway-gates.

In the drawings, which accompany and form part of this specification and in which similar figures of reference refer to corresponding parts in the several views, Figure 1 shows in side elevation, a pair of gates located on their posts at opposite sides of the highway crossing, together with the main weight-casing and operating-levers and tripping devices. A portion of the casing is broken out to show the connections. Fig. 2 shows a plan view of four gates located on opposite sides of the highway and opposite sides of the railway, together with the casing and operating-levers of the main operating-weight. Fig. 3 shows a section of the main weight-casing and the gate-post casing and the connecting-casings, exposing to view the gate-weight and the main weight and connections between them, the gate being shown in position to close the highway-crossing. Fig. 4 shows the same parts shown in Fig. 3, with the gate open. Fig. 4^a shows details of a hand-lifting lever. Fig. 5 shows in detail a side, plan, and end view of the outlying lever in connection with the section of rail adjacent to which the lever is located. Fig. 6 shows in detail a pair of pivoted levers for operating the weight-catch, to which the cables or connections extending to the outlying levers are attached. Fig. 7 shows the outlying lever. Fig. 8 shows the weight-lifting lever. Fig. 9 shows a crank-arm on the end of the outlying-lever shaft, together with a portion of the cable or connection. Fig. 10 shows a toe or arm projecting from the shaft of the weight-lifting levers

adapted to engage the main weight. Fig. 11 shows a plan view of the outlying levers and connections. Fig. 12 shows a plan view of the weight-lifting levers and connections. Fig. 13 shows a cross-section of the gate-post and weight, together with a top view of a portion of the gate. Fig. 14 shows a side view of the parts shown in Fig. 13. Fig. 15 shows details of a catch and hand-tripping device.

Referring more specifically to the reference-numerals marked on the drawings in a more particular description of the device, 1 indicates the rails of a railway-track, a double track being shown in the drawings.

2 indicate the gate-posts, located at opposite sides of the highway and opposite sides of the railway. One gate-post only may be used on either side of the railway, in which case a longer gate is used. The gate-post consists of a hollow column having a closed upper end, which provides a tight-air chamber, in which runs gate-weight 3. From gate-weight 3 project, through suitable slots in the gate, post or column pins 4, which are adapted to engage and run on the upper edge of the gate-bars 5, the gate being forked at its rear end and having a bar passing to each side of the gate-column.

7 are counterweights to the swinging end of the gate, the excess of weight being in the swinging end which projects across the highway.

The gate is provided with a hinged joint 8, which allows the gate to be pushed open from the railway side of the gate, the gate being held in its normal position by spring 9. The lower end of the gate post or column 2 is connected with a water-tight underground connecting-casing 10, which extends to the main-weight column 11, to which it is connected by a water-tight joint. At the angle between the gate-column and the horizontal casing 10 is provided a bell-crank lever 12, pivoted to the casing at 13. To one end of the bell-crank lever 12 is attached a bar or rod 14, which extends to the gate-weight 3, and has its end received in a pocket 15 in the lower end of the gate-weight. The rod is not otherwise connected to the weight. The opposite end of the bell-crank 12 is attached to a connection 16, extending to bell-crank lever

17, pivoted at 18 at the angle in the casing 10, adjacent to or beneath the main operating-weight 19. From the opposite end of the bell-crank lever 17 extends a rod 20, which enters a suitable sleeve or pocket 21, provided in the lower end of the gate-weight 19. The rod or bar 20 is not connected with the gate-weight, except by entering the sleeve. Two or more bell-cranks, as 17, may be provided 10 in the casings beneath the weight 19 to provide suitable connections for extending to opposite sides of the railway or highway, as circumstances may require. The main operating-weight 19 is engaged by a toe or arm 22, mounted on the end of a shaft 23, which extends across under the several tracks and is provided adjacent to one of the rails of each track with an arm 24, to the free end of which is connected a link 25, which connects with a 15 pair of levers 26, lying adjacent to the rail of the track and adapted to project above the surface of the rail and receive the tread of the wheel moving on the track. A hand-lever 22^a, pivoted to the side of the casing and 20 having its bell-crank arm engaging in the weight, is provided as a hand-lifter for the weight 19. The weight 19 is also provided with a projection 27, extending through a slot in the casing 11 and adapted to be engaged 25 by catch 28, pivoted to a projection from the casing at 29, and having an inclined face 30, adapted to be engaged by the projection and to throw back the catch as the weight is elevated.

30 31 is a spring for returning the catch 28. 32 is a hand-tripping device pivoted at 33, having a projection 32^a, adapted to engage and operate the catch. Adjacent to the swinging end of the catch 28 is provided a pair of levers 34 and 35, pivoted at 36 to a projection from the casing 11. The levers 34 and 35 are adapted to engage the catch 28 and disengage it from the projection 27 of the weight. To the ends of levers 34 and 35 are connected cables 37 and 38, which extend in opposite directions along the track to the outlying levers located at suitable distances on either side of the gate. The cables 37 or 38 connect with an arm 39 on the outlying lever-shaft 40, which 40 shaft 40 extends across under the tracks and is provided with a crank 41, connected by link 42 with outlying lever 43, lying adjacent to one of the rails and projecting above the face thereof and adapted to receive the tread of 45 wheels on the track. The outlying lever 43 is provided with a curved end 43^a and is mounted adjacent to its curved end on a long pivotal pin 45^a, provided on the link 42, whereby the end of the lever is free to vibrate away 50 from the track when it is approached by wheels in the wrong direction. The lever is held adjacent to the track by a spring 44.

55 The operation of the device is substantially as follows: The gate being in open position, (shown in Fig. 4,) as a train of cars approaches the gate the wheels thereof tread upon outlying lever 43 and depress the same, which op-

erates upon the connection 37 or 38, as the case may be, and through the levers 34 and 35 disengages the catch 28, which at the time 70 is supporting the main weight 19. When the catch 28 is disengaged, the weight 19 rests upon the upper end of rods 20 and through the connections 20, 17, 16, 12, and 14 raises the several gate-weights 3. The weight of the 75 weight 19 is greater than the combined weights of the several gate-weights 3 to be operated thereby, so that as the main weight 19 descends the several gate-weights are elevated. The speed with which they are elevated is regulated and cushioned by the air contained with 80 in the air-chamber in the upper end of the column, which may be allowed to escape slowly through an opening provided for the purpose, or the weight may be fitted somewhat loosely 85 in the column to permit the escape of the air along the sides of the weight. As the weights 3 are elevated the pins 4 are raised off the edges of the gate-arms and the gates closed by their own gravity. When the train passing 90 along the railway-tracks has reached the gate, the wheels tread upon the gate-weight levers 26, and by depressing them they elevate the main weight 19 through the several connections heretofore described. As the weight 19 95 is elevated it is held up by catch 28. As the weight is elevated the ends of connections 20 slide in the sleeve-like openings in the lower end thereof. After weight 19 is elevated the gate-weights 3, being unsupported, descend, 100 and the pins 4, operating upon the gate, swing the same on their pivots and open the gate. The movement of the weights 3 in this direction is also regulated by the air-chamber in the upper end of the gate-column, as before 105 mentioned. The air-chamber in the upper end of the gate-column causes the gates to open and close with a slow and regular movement.

A train approaching the outlying levers 110 from the gate side of the lever will not operate them, as the wheels come in contact with the inclined or bent end of the lever and swing it to one side on the pin 42^a without depressing the lever and thus operating the 115 gate mechanism.

The gate may be tripped by depressing treadle 32 to disengage the catch 28.

Mechanism may be provided for elevating the weight 19 by hand and independent of 120 the levers 26.

It is evident that many changes and modifications in and from the construction described may be made without departing from the equivalents of my construction.

What I claim as new, and desire to secure by Letters Patent, is—

1. The combination in a railway gate of a gate weight and a main weight and connections between the main and gate weights engaging the weights by entering sleeve-like openings in the lower ends of the weights, substantially as set forth.

2. A set of vertically swinging gates, a mov-

- able counterweight for each gate, a separate housing for each weight providing an air cushion for the same, a main weight, connecting mechanism between the main weight and each gate weight constructed and arranged to elevate the gate weights when the main weight descends and permit an independent raising of the main weight, a catch for securing the main weight in elevated position, tread-levers and mechanism connecting them to the main weight for elevating the weight, track tripping levers and a connection to the catch, combined, substantially as set forth.
- 15 3. The combination in a railway gate, of a gate, a main weight, and an operating connection extending between the gate and the weight and entering a socket in the end of the weight whereby the weight is permitted an independent movement in one direction without becoming disconnected, substantially as set forth.
4. The combination of a railway gate, gate and main weights 3 and 19, the bell-crank levers and connections between the bell-crank levers and between the levers and weights, and the weight raising and tripping devices operating on weight 19, substantially as set forth.
- 25 5. The combination in a railway gate of

the vertically swinging gate, the gate weight 3 working in an air cushioned chamber, an opposing main weight 19, bell-crank levers, connections between the weights and bell-crank levers, a tread-lever lying adjacent to the track and a rock shaft, a crank for raising the weight 19, a catch for securing the weight, a tripping lever lying adjacent to the track with the end farthest from the gate lower and pivoted, the opposite end being adapted to rise above the plane of the track and beveled, a connection between the tripping lever and the catch, substantially as set forth.

6. In a railway gate, the combination of two or more stationary cylinders adjacent to the crossing, housing connecting the cylinders, two or more movable counterweights, a main weight having an excess of weight over all the counterweights, connections between the main weight and counterweights through the housings, a connection between each counterweight and each gate and mechanism for operating and tripping the main weight, substantially as set forth.

In witness whereof I have affixed my signature in presence of two witnesses.

GEO. A. REYNOLDS.
